UNITED STATES PATENT OFFICE.

CHARLES E. EGAN AND ELVA F. JACKSON, OF CHARLESTON, WEST VIRGINIA,
ASSIGNORS OF ONE-THIRD TO LEWIS C. SUMMERS, JOHN R. CRISWELL, AND
JOHN W. PAULEY, ALL OF CHARLESTON, WEST VIRGINIA.

SUBMARINE MINE.

1,306,372.

Specification of Letters Patent. Patented June 10, 1919.

Application filed August 3, 1917. Serial No. 184,811.

To all whom it may concern:

Be it known that we, CHARLES E. EGAN and ELVA F. JACKSON, citizens of the United States, residing at Charleston, in the county 5 of Kanawha and State of West Virginia, have invented new and useful Improvements in Submarine Mines, of which the following is a specification.

This invention relates to weapons of war, 10 the object being to provide a submarine mine which may be dropped from a vessel, aeroplane or other means of transporting it over or above the sea, or be expelled from a gun, and may be controlled for explosion 15 after reaching a predetermined depth under water, a predetermined interval of time after launching, or at the will of an operator who directs the launching.

The mine consists of an air tank containing 20 compressed air or other gaseous medium under pressure, which tank is detachably connected with a bomb containing a high explosive, and means for disconnecting the two, external means as a shot directed at the 25 tank after launching, or automatically after a fixed time interval, thereby releasing air pressure in the tank and acting on a trigger setting free the bomb from the floating element of the tank and permitting it to sink 30 in the sea; during the sinking operation of the bomb, slack is paid out from a coil of twine in the head of the bomb, and when all is paid out, the twine is rendered taut and operates a circuit closer within the 35 bomb, exploding a charge of dynamite, nitro-glycerin, or other desired explosive. The considerable depth under water at which the explosion occurs insures an instantaneous development of great hydrostatic 40 pressure by the body of superincumbent water and the enormous energy set free in the explosion instantaneously radiates in all directions and is communicated to any hostile vessel or submarine in the neighborhood, 45 acting to crush in its walls.

The invention, therefore, consists of a float and a detachable bomb or torpedo which, at a predetermined time or at the will of an operator, may be released to 50 gravitate downward to a considerable depth of sea, and means for then exploding it. It comprises also means such as a flexible line coiled in the bomb-head, which is paid out as it sinks until all of the line slack is

taken up, when the bomb is exploded; it comprises other specific features which will be hereinafter more fully detailed and will be fully indicated in the claims. 55

In the accompanying drawings illustrating the invention, 60

Figure 1 illustrates partly in section a combined float and bomb embodying our invention with the several elements in relation prior to immersion.

Fig. 2 is a sectional view on a plane at 65 right angles to that illustrated in Fig. 1 showing a condition of the float and bomb, in normal position in full lines, and in dotted position after launching and while the line which controls the explosion is being 70 paid out.

Fig. 3 is a sectional view of the top of the air tank showing in plan the trigger-mechanism for releasing the bomb.

Fig. 4 is a detail view of a timing mechanism governing the explosion at will. 75

Fig. 5 is a sectional detail in the plane 5-5 of Fig. 4 showing the structure of the valve mechanism.

Fig. 6 is a sectional detail showing the 80 relations of the trigger mechanism in the air tank at the time of launching.

Referring now to the drawings, and first to Fig. 1, 1 represents an air-tight tank having a reentrant chamber at the top, over 85 which is a screwed lid 2 engaging a vulcanized rubber seat 3, and 4 is a strong metallic vessel of steel or heavy iron constituting a bomb. The bomb and air tank are normally thrust together by sliding two stout rods 5, 5^a bolted or otherwise rigidly secured to the head of the bomb into internal tubes, as shown, in the air tank, as better seen in Fig. 2. The head of the bomb has a flat seat 6 covered with a thin packing of soft rubber 7 to prevent infiltration of water between the two parts after launching. The bomb body 4 contains a charge of gun-cotton or other high explosive 8. In the bomb-head at the top is supported on insulating material 9 a circuit-closer 10, the yielding element of which is connected to a flexible cord 11. The fixed end of the circuit-closer is connected by wire with the metallic bomb-casing. The anvil of the circuit-closer 12, 105 mounted on the insulated support 9, is in operative relation to the lever 10, so that when the cord 11 is paid off and rendered

taut, the circuit will be closed from the bomb case, battery 13, through 9, through a dynamite cap 14 in which the heat of a closed current explodes the cap, thereby exploding the high explosive charge of gun-cotton, nitro-glycerin or other explosive within the bomb.

The tank 1 may be filled with compressed air, or other gas, by a bicycle valve 15 soldered into the base of the tank. On the side of the tank is an air valve 16 governing the rate of leakage of the compressed air with which it is filled. This valve is shown in section in Fig. 5, and comprises a tapered stem 17 co-operating with the tapered hole in the bottom or recess in the tank wall. An adjusting screw 18 permits this to be nicely adjusted to govern the rate of leakage of air through the fine opening around the pin at 17 and thus through an opening in the screw support and the wall of the tank to the external atmosphere. Under the head of the screw is a scale, as indicated in Fig. 4, showing the positions of adjustment and consequent rate of leakage of air through the needle-valve. When screwed tight, the charge would remain undisturbed in the tank, but by adjustment to various determined positions on the scale of Fig. 4, any interval desired up to an hour for reduction of pressure in the air tank, which determines the release of the bomb from the floating element, is secured.

The rods 5, 5^a, constituting the connection with the floating tank, pass through tubes within the tank. At the top these rods are grooved and when the rods are pushed home, the rubber seat 7 is brought up into firm engagement with the base of the float and forms a water-tight connection. In this position two pivoted arms 19, 19^a, urged by a spring 20, snap under the recessed grooves at the top of the rods and lock them so that the bomb is in tight relation to the tank. These rods 19, 19^a are pivotally secured to a connecting bar 21 which carries a cam 22 so that when the cam is shifted laterally by its sloping face, disengagement of the rods 5, 5^a with the floating element is effected. This release is determined either automatically or at will upon predetermined reduction of air-pressure in the tank. Thus, if at a certain interval after launching the mine the launching operator deems the moment fit to explode the charge, he can immediately direct that a rifle be discharged at the float by which the tank will be punctured, thereby securing reduction of air-pressure and permitting the bomb to sink. On the other hand, if the valve-mechanism hereinbefore described is to be used after the set interval of time, the disconnection of the bomb and its discharge after sinking a given depth, is effected.

65 The mode of effecting the discharge at a

considerable depth under the sea level is determined by a flexible line 23, the lower end of which is fastened to the circuit closer 10 of Fig. 1, and which passes through a rubber gasket in a small hole in a cup 24 in the bomb-head. Thence the cord is coiled in this cup and attached to an eye in the base of the float.

The means for determining the disconnection of the bomb and float are shown in detail in Figs. 2 and 3. A spiral spring, mounted in a support 25 on a platform in the inner wall of the float, is rigidly attached at one end of the spring to the platform, as indicated at 26, and the free end 27 forms an arm which engages a pivoted bail 28. This bail carries an integral arm which overlaps a trigger 29 pivoted in a seat at 30. Thus, by grasping the bail 28 and drawing the spring until it lies flat on the platform, then moving the trigger arm until it engages a detent 31, the spring will be locked under tension by a latch which will now be described.

This latch consists of a movable rod 32 supported on a corrugated diaphragm 33 having a tubular opening 34 into the air compressed chamber of the tank 1. Two of these diaphragms 33 are soldered together at their circular edges. Therefore, under the air-pressure the diaphragms are pushed apart, raising the rod 32 against the bias of a helical spring 35 until it passes and obtrudes or locks the latch 29 against dropping off under jar through the bias of its retracting spring 36. This is a leaf spring and stands in a vertical position being secured at its base to a slotted plate by which its tension may be adjusted by means of a screw 37. With this construction, when the bomb and float are assembled, it will be seen that the arms 19, 19^a hold it locked in the assembled relation and that the air-pressure maintained in the tank 1 intercepts the latch 29 by raising the rod 32. The latch, therefore, is firmly locked, but upon reduction of air-pressure in the tank, the diaphragm no longer being expanded, permits the rod 32 to lower, thereby uncovering the latch 29 and permitting its spring 36 to push the latch out of the recess 31, whereupon the strong spring bias under which the bail 28 has been put, throws the latter instantly with a violent blow, somewhat after the manner of construction of a common mouse trap, and delivers a hammer blow upon the cam 22 at its sloping wall, thereby forcing the cam to move laterally and opening the engagement between the locking arms 19, 19^a with the two rods 5, 5^a carried by the bomb. Thereupon the bomb will be free to move away from its float and sink, and in doing so, the slack is taken up from the coil of cord 23 in the bomb head. This coil of cord may be of any desired length to the purpose that the

5 bomb may be exploded at any given depth under the surface of the sea. The greater the depth, the more violent will be the hydrostatic pressure of the explosion and the greater damage will result. The length of line, therefore, will be predetermined by the launching operator. As the bomb sinks, when a depth is attained by which all of the slack in the line 23 is taken up, the circuit-
10 controller will be raised into contact with its anvil 12 thereby instantly detonating the cap 14 and exploding the explosive charge of dynamite, nitro-glycerin, or other desired explosive.

15 In some cases it may be desirable to launch the mine by means of a catapult, pneumatic gun or other launching means by which it may be thrown a considerable distance. We desire that our invention may be construed 20 with reference to any desired means of launching the mine.

Having thus described our invention, what we claim as new and desire to secure by Letters Patent, is:

25 1. A submarine mine comprising a float filled with compressed air, an attached bomb adapted to sink when released, a detent controlling the release upon reduction of air-pressure in the float, a slack cord rendered 30 taut at a given depth under water, and means within the bomb to explode the charge of high explosive when the cord is taut.

35 2. A submarine mine comprising a hollow float, an attached bomb connected to the float and adapted to sink when released, a latch and detent therefor normally maintaining the connection, elastic means under fluid pressure in the float normally holding the latch in engagement, whereby upon reduc-

tion of fluid pressure the latch is released to 40 disconnect the bomb, flexible means paid out on release of the latch, and detonating means to explode the bomb when the flexible means is fully paid out.

3. A submarine floating mine adapted to 45 be planted in hostile water comprising a floating tank of compressed air, an attached bomb filled with high explosive, a trigger adapted to disconnect the bomb, a detent for the trigger released on reduction of air-pressure, a spring actuated on release of the trigger adapted to positively mechanically operate the bomb connection with the float, permitting the latter to sink to a predetermined 50 depth of submergence, and means for operating a cap to explode the bomb when so submerged.

4. A submarine floating mine adapted to be launched in hostile water, means for filling the floating element with compressed air, 60 a diaphragm distended by the air-pressure, a trigger held locked when the diaphragm is distended, and released when retracted, a spring held under tension when the trigger is locked adapted to give a hammer-blow on 65 a latching device, a bomb connected to the floating element by the latching device, a flexible line in the head of the bomb adapted to be paid out on release of the latching device, whereby the bomb may sink in water, 70 a circuit-closer operated when a given depth of bomb submergence is reached and the line made taut, and a cap to explode the bomb operated by the circuit-closer.

In testimony whereof, we affix our signatures. 75
